CARTON

Perry Belden, Lansdale, Pa., assignor to National Union Radio Corporation, Newark, N. J., a corporation of Delaware

Application June 1, 1944, Serial No. 538,274

4 Claims.

(CL 229—6)

The present invention relates to a carton designed primarily for the packaging of cathode ray tubes.

Tubes of that character have an envelope the geometry of which includes an extended neck portion, an adjoining enlarged conically shaped portion, and a top or screen portion. Because of this variation in tube diameters, it is necessary to provide a form of suspension adapted to give support to the tube at several points of contact of different diameters, and hold the tube in proper axial alignment to prevent breakage during the shipping and storage thereof.

In my copending applications, Serial Numbers 500,467, and 507,672, filed August 30, 1943, and October 26, 1943, respectively, I have disclosed several constructions of cathode ray tube cartons embodying the general construction of multipoint suspension. The present invention is an improvement of this constructional feature.

An object of the present invention is the provision of a carton consisting of an outer container having an inner filler member adapted to afford multipoint suspension, of such a character that the suspending means also furnishes locking means for positioning and holding the contained tube firmly in position.

Another object is the provision of a filler member stamped from a single blank piece of paperboard, which blank is suitably scored to provide a transverse supporting platform having reinforcing members each designed to form a tuck when reversely folded, said tucks having cut-out supporting portions along the folds and the free end of each tuck extending sufficiently rearwardly to abut against the opposing side wall of the outer container.

Another object of the invention is the provision of a filler having wing members integrally formed with a supporting platform, which members are adapted to serve as supplemental supporting means for the tube and also function as resilient means in supporting the end closure members in such a manner that it is unnecessary to use any sort of packing material between the top or screen portion of the tube and the closure members.

Other objects, such as simplification of construction, economy of material and reduction in time required for the packaging operation will manifest themselves as the description proceeds.

Referring to the accompanying drawing:

Fig. 1 is an extended view or development of a one-piece blank adapted to be folded into a filler member embodying the invention;

Fig. 2 is a perspective view, partly cut away, showing the blank of Fig. 1, folded to form a filler member ready to be inserted into an outer container.

Fig. 3 shows the filler member partly inserted 5 within the outer container;

Fig. 4 is an elevational view, partly broken away, illustrating the tucking arrangement for the top portion of the folded blank;

Fig. 5 is a view similar to Fig. 4, showing more 10 completely the folded filler before sealing of the carton; and

Fig. 6 is a vertical cross-sectional view of a 15 completely assembled package including a cathode ray tube supported therein, the tube being shown in elevation.

The carton illustrated may comprise an outer container 1 having side walls 2 and cut-out closing end flaps 3, the general contour of the container being tubular. An inner supporting filler member referred to generally by the reference character 4 is of a telescopic form and may comprise a one-piece blank 5 of paperboard, such as corrugated board. The blank 5 is provided with score lines 6 which form corners in bending and the spacing of the lines 6 is such as to form sections having different functions. For example, section 7 comprises a supporting side wall extending substantially the full length of 20 the container 1. It is, of course, appreciated that the width of the blank 5 is substantially equal to one of the inside dimensions of the outside container 1, which is customarily square in cross-section. Regardless of the cross-sectional shape 25 of the container 1, the various sections, formed by folding the blank 5 along the score lines, are equal in length to the design of the carton, with respect to the geometry of the article packaged.

Succeeding the supporting wall 7 is a transverse supporting platform 8 provided with a circular aperture 9, the center of which coincides with the longitudinal axis of the container 1. Following the platform 8 is a spacing member 11. It will be observed that the width of 40 the transverse supporting platform 8 is the same as the inner width of the container 1, and when the spacing section 11 is folded along its upper score line, it depends downwardly a distance sufficient to afford proper spacing for the succeeding section 12, which constitutes an oblique or diagonal portion. I prefer to make the angle of inclination of the diagonal member 12 substantially 45 degrees or slightly thereunder, because I found that inclination most satisfactory from 45 practice based upon theoretical considerations.

The diagonal section 12 has an oblong or elliptical aperture 13. It will be noted that the minor axis of the elliptical aperture corresponds to the diameter of the neck of the cathode ray tube 14 and the apertures 9 and 13 have a common axis when the filler member 4 is telescoped within the container 1.

In order to strengthen the diagonal member 12, each of the outer edges thereof is provided with a wing 15, adapted to fold downwardly to afford reinforcement to the diagonal section 12. To augment the reinforcing effect of the wing members 15, the edges thereof are cut at an angle so as to abut against the inner side wall of the container 1 (see Fig. 2).

Adjoining the diagonal section 12 is another spacing section 16. The width of the spacing section 16 is such that when it is folded along the score lines 6, it will produce a corner for transverse section 17, which corner rests on the bottom of the container 1, thus giving support to the super-structure and is held from displacement by the end of the transverse section 17 abutting against the opposite side of the container 1.

The special means for suspending the tube 14, which constitutes a distinguishing feature or improvement over the disclosure of my above identified copending applications, resides in the laterally extending wings 18 provided on the outer edges of the transverse supporting platform 8. The wings 18 are provided with score lines 19 which divide each of the wings 18 into longitudinal sections 20 and 21 of substantially equal width so that when sections 20 and 21 are reversely folded with respect to each other, they form a tuck, the apex of which coincides with the score lines 19. Each of the sections 20 is provided with a die-cut semi-circular aperture 22 which is of sufficient diameter to afford appreciable contacting edges for engaging the periphery of the top of the tube 14 when the latter is inserted in the filler 4, as hereinafter more fully explained. In making the apertures 22, I prefer to retain the cut-out portions to form tabs 23 which are hinged along the score lines 19. This may easily be done by not extending the die-cut beyond the score line 19.

When the filler member 4 is folded for insertion into the outer container 1, it takes the form or shape shown particularly in Fig. 2. Thus folded, it is set into the outer container (see Fig. 3) and while in that position, the tube 14 may be inserted so that the neck portion of the tube extends through the elliptical aperture 13, and the upper conical portion of the tube comes into engagement with the circular aperture 9. In this position, the tube may be used as means for pressing the filler 4 all the way into the outer container 1 (see Fig. 4). At this stage of the packing operation, the wings 18 are each folded along the score lines 19 with the result that tucks are formed, the edges of which slightly extend beyond the perimeter of the top of the tube 14 so that the apertures 22 engage with the opposing portions of the perimeter and form points of support for the tube (see Fig. 6). It is obvious that the tabs 23 are pushed upwardly and rearwardly by the engaging portions of the perimeter of the tube 14, which cause the tabs to extend laterally from the apexes of the tucks. The tabs 23, thus projecting laterally, contact the top face of the tube 14, exerting a downward pressure, thereby affording supplemental locking means for holding the tube in proper alignment within the carton.

As indicated above, the sections 20 and 21 form-

ing the wings 18 are of sufficient width that when the wings 18 are folded into a tuck, the sections 21 are inclined upwardly and engage the inner corner of the adjacent end closure flaps 3. When the end flaps 3 are folded downwardly, closing the outer container 1, the abutting edges of the sections 21 constitute a flexible anchorage, the effect of which is to exert an appreciable downward pressure so that an element of resiliency is imparted to the wing members 18 and the tube 14 is thus resiliently, but firmly, supported within the carton.

To facilitate the removal of the tube 14 from the carton, I provide the expedient of cut-out apertures 25 along the outer edge of the sections 21. By inserting one's fingers into the apertures 25, it is a simple operation to pull up the wing sections 18, thereby affording easy access to the tube.

From the foregoing description, it is obvious that the tube 14 is supported at a number of points so that the weight thereof is distributed among multiple points of suspension, thus relieving any excessive strains that might occur if the suspension of the tube consisted of merely a one point suspension, as for example, being supported only from the circular aperture 9 in the transverse supporting platform 8.

The several points of suspension may be pointed out as constituting the engaging elliptical aperture 13, the circular aperture 9, and the semi-circular apertures 22. The downward cantilever action, applied by sections 21 anchored against the inside corners of the closure flaps 3, resist any displacement of the tube 14 that may be caused by an upward movement, occasioned for example by the carton's being set upsidedown with respect to the way the tube is packaged.

To those skilled in the art, it will be appreciated that in the packaging of cathode ray tubes the prongs at the base of the tube should at all times be out of contact with the bottom of the carton, because when the prongs do come in contact with the bottom, the glass seal surrounding the collar portion of the base is very apt to become cracked, which leads to defects destroying the efficiency and/or life of the tube.

Modifications in the construction of my carton will suggest themselves to those skilled in the art, but it is my intention to cover all such modifications as come within the scope of the appended claims.

What is claimed is:

1. A carton for cathode ray tubes comprising an outer container member having side walls and cut-out closing end flaps, an inner supporting filler member of a telescopic form and consisting of a one-piece scored blank adapted to form a series of sections when folded along the score lines, one of said sections constituting a transverse supporting platform having laterally extending wing sections provided with score lines adapted to form a tuck when the wing sections are reversely folded with respect to the support platforms, segmental die-cut portions arranged with an edge thereof hinged on said score lines and adapted to form tabs extending laterally from the apex of the tuck, apertures based upon the score lines of the wing sections and resulting from the formation of said tabs, said apertures constituting supporting means for the inserted top edge of a cathode ray tube, and the tabs affording supplemental locking means for holding the tube in proper alignment within the carton.

2. The construction claimed in claim 1, where-
in the wing sections of the supporting platform

are provided with score lines which divide them into portions of substantially equal width when folded into a tuck, the apex of said tuck extending to a supporting position for the top edge of the tube and the free end of the upper tuck portion abutting against the inner corner of the adjacent end closure flaps of the outside container, whereby the tube is resiliently anchored against longitudinal displacement.

3. A carton for cathode ray tubes comprising an outer container member having side walls and cut-out closing end flaps, an inner supporting filler member of a telescopic form and consisting of a one-piece scored blank adapted to form a series of sections when folded along the score lines, one of said sections constituting a transverse supporting platform having laterally extending wing sections scored longitudinally and adapted to form a tuck when reversely folded with respect to

5 the supporting platform, segmental die-cut portions arranged with their chords coinciding with the score lines of the wing sections, the die-cut portions being hinged along their chords and adapted to form tabs extending laterally from the apex of the tuck thereby providing apertures based upon the score lines, said apertures constituting supporting means for the inserted top edge of a cathode ray tube, and the tabs affording supplemental locking means for holding the tube in proper alignment within the carton.

4. The construction claimed in claim 3, wherein the apexes of the tucks are oppositely disposed with respect to each other, and the free end of the upper portion of each tuck abuts against the inner corner of the adjacent end closure flap of the outer container, whereby the tube is resiliently anchored against longitudinal displacement.
